(57) CLAIM

The ornamental design for a chair as shown and described.

DESCRIPTION

FIG. 1 is a front, left, and top perspective view showing my new design.

FIG. 2 is a front view showing my new design.

FIG. 3 is a rear view showing my new design.

FIG. 4 is a left side elevational view showing my new design.

FIG. 5 is a right side elevational view showing my new design.

FIG. 6 is a top view showing my new design; and,

FIG. 7 is a bottom view showing my new design.

The shading lines shown in the drawings represent the approximate three-dimensional contour of the design, and are not intended to indicate surface decoration.
